US00D885923S

(12) **United States Design Patent** (10) Patent No.: **US D885,923 S**
(45) Date of Patent: **** Jun. 2, 2020**

(54) **CONTAINER**

- (71) Applicant: **Runway Blue, LLC**, Alpine, UT (US)
(72) Inventor: **John R. Omdahl, II**, Lindon, UT (US)
(73) Assignee: **Runway Blue, LLC**, Alpine, UT (US)
(**) Term: **15 Years**
(21) Appl. No.: **29/675,224**
(22) Filed: **Dec. 28, 2018**

(57) **CLAIM**

The ornamental design for a container, as shown and described.

DESCRIPTION

FIG. 1 is a top perspective view of a container showing my new design;

FIG. 2 is a front view of the container shown in FIG. 1;
FIG. 3 is a rear view of the container shown in FIG. 1;
FIG. 4 is a left side view of the container shown in FIG. 1;
FIG. 5 is a right side view of the container shown in FIG. 1;
FIG. 6 is a top view of the container shown in FIG. 1; and,
FIG. 7 is a bottom view of the container shown in FIG. 1.
The broken lines in the drawings depict portions of the container that form no part of the claimed design.

1 Claim, 6 Drawing Sheets
